UNITED STATES PATENT OFFICE.

ARTHUR JEAN BAPTISTE FAURE, OF PARIS, FRANCE.

RUBBER-SOLED SHOE.

1,125,993.

Specification of Letters Patent.

Patented Jan. 26, 1915.

Application filed December 20, 1912. Serial No. 737,847.

To all whom it may concern:

Be it known that I, ARTHUR JEAN BAPTISTE FAURE, a citizen of the French Republic, and residing at 60 Rue de Rébeval, Paris, Department of the Seine, France, have invented a certain new and useful Improvement in Rubber-Soled Shoes, of which the following is a specification.

The present invention has for its object a boot sole with an extended extra sole or tread formed by a single layer of india-rubber.

Attempts have already been made to attach india-rubber soles under leather soles of shoes so as to make them waterproof. When such india-rubber soles are simply secured by a cement they are not durable because the cement becomes loosened after a short period. When they are sewn or nailed they are secured only under the forward part of the sole and do not cover the bent part of the latter which, as a consequence, is not waterproof. Moreover, the parts of india-rubber soles sewn or nailed have been secured by means of a leather edging which wholly surrounds them, with the result that a thick leather edge is located under the bent portion of the sole ungraceful to see and inconvenient to the wearer of the shoe.

The present invention has for its object an india-rubber extended sole which wholly covers the leather sole and, as a consequence, makes it fully waterproof without giving extra thickness or a raised edge at the place where the sole bends.

The object of the invention is illustrated by way of example in the accompanying drawings.

Figure 1 is a longitudinal section of the sole and of a part of the upper leather. Fig. 2 is an inverted plan of the india-rubber sole. Fig. 3 is a section through the line A—A in Fig. 1.

The upper leather 1 of the boot is sewn in the usual manner on to the welt 2. An under-sole 3 is then placed against the welt. On to this under-sole the extra extended india-rubber sole or tread 4 is fixed. This india-rubber sole is molded in a single piece

of a thickness varying according to the strength of the boot for which it is intended. It has on its circumference a part 5 that is cut away or made thinner for the purpose of receiving a leather edging 6 and for insertion in the heel. The whole comprising the under-sole, the extra extended india-rubber tread and the edging is sewn on to the welt like an ordinary sole. The heel is formed by a false lift 7, of the same thickness as the cut away part of the extended rubber sole, on which the ordinary lifts 8 are arranged.

The heel is nailed on in the usual way. On the under-sole a filling 9 is arranged, above which the in sole 10 is put in the usual way.

The whole forms a supple, strong and absolutely impermeable sole.

The sole 4 being firmly secured by being sewn between the under-sole 3 and the edging 6 is free from the inconvenience that exists in india-rubber soles which are attached by adhesives as such soles become loose in a relatively short space of time.

A boot provided with a sole constructed in accordance with this invention can be very easily re-soled. All that is necessary for this purpose is to detach the worn parts of the india-rubber sole and the edging and to replace them by new parts of suitable shapes and dimensions. The connection of the old and new india-rubber is effected by beveling the edges and attaching them together adhesively.

An india-rubber sole may also be applied to an ordinary leather boot in consequence of the employment of a continuous edge which entirely surrounds the sole (see the part of Fig. 2 comprised between the end of the sole and the dotted lines) and which is sewn on to the edges of the sole and nailed to the bend.

What I claim and desire to secure by Letters Patent is:

A rubber soled shoe, comprising, in combination, a leather under-sole, a welt, an india-rubber sole molded in one piece and having its entire peripheral edge thinned, a heel provided with a recess to receive the

thinned rear end of said rubber sole, a leather edging located over all of said thinned peripheral edge except that portion located in said heel recess, a seam securing said leather edging to said welt and passing through said leather under-sole and said thinned peripheral edge of said rubber sole, and means driven into said heel and said

thinned rear end of said rubber sole to secure the latter to said heel.

In testimony whereof I affix my signature in presence of two witnesses.

ARTHUE JEAN BAPTISTE FAURE.
